CLAIM

The ornamental design for a cleaning unit for shaver, as shown and described.

DESCRIPTION

FIG. 1 is a perspective view showing a cleaning unit for shaver according to our design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.
The broken lines illustrate portions of the cleaning unit for shaver that form no part of the claimed design.

1 Claim, 5 Drawing Sheets
